ATTRITION MILL APPARATUS AND METHOD
Thomas W. Hopwood, Box 538, Giddings, Tex.
Filed Feb. 8, 1963, Ser. No. 257,267
21 Claims. (Cl. 241—5)

This invention relates to new systems and methods of pulverization by attrition, classification of the powdered product, drying, delamination, chemical treatment, batch mixing and continuous mixing, of materials and to compact arrangements of apparatus comprising efficiently operating combinations of attrition mill, and apparatus used in connection therewith for carrying out these methods.

Centrifugal fluid jet action has been extensively used in apparatus for pulverizing or size reduction of solid material particles. Jets of gaseous fluid are usually introduced at high velocity into an annular grinding zone in an outer portion of a treatment chamber of circular cross section, said grinding zone containing material to be pulverized in the form of discreet small particles. The high velocity fluid jets are usually introduced in directions inclined forwardly with respect to the radii of the treatment chamber, so as to maintain the fluid in the chamber whirling rapidly in the direction of such forward inclination. The grinding zone is of limited axial length and is confined by peripheral portions of the chamber walls enclosing said zone at its outer circumference and both axial ends, and gaseous fluid is continuously withdrawn inwardly from the grinding zone and discharged from the treatment chamber, preferably through a centrally disposed fluid outlet. The gaseous fluid thus has a generally inwardly spiralling movement within the treatment chamber, and the material undergoing pulverization is preferably continually supplied to the moving fluid within the treatment chamber.

The high velocity fluid jets effect a reduction of particle size of the material under treatment by impact and attrition of particles against one another and against the chamber walls, while at the same time causing the charge of material to rotate rapidly within the grinding zone in the direction of the whirling movement of the fluid. The material must be prepulverized and predried. Due to the centrifugal effects resulting from the rapid rotation of the charge within the grinding zone, the larger particles are caused to circulate in said zone where they come repeatedly under the influence of the introduced high velocity jets of gaseous fluid and are thus repeatedly subjected to the size reducing action produced thereby, while the material which is sufficiently reduced in size is entrained by the gaseous fluid as it spirals inwardly toward the centrally disposed fluid outlet.

The entraining action of the inwardly spirally gaseous fluid exerts on the suspended particles of the circulating material within the pulverizing zone a radially inward component opposing the radially outward component of force due to centrifugal action, and continuously removes from the grinding zone particles which are sufficiently reduced in size, entraining such particles in its movement toward the fluid outlet and effecting a very intense fluid-sweeping action of the charge within the chamber, together with a high degree of centrifugal classification of the entrained material. A portion of the chamber radially inwardly of the grinding zone usually communicates with an axially extended centrifugal product collector of smaller diameter than the chamber, which utilizes the whirling energy of the gaseous fluid entering said collector to separate a considerable portion of the entrained

2

material from the carrier fluid, while the fluid, more or less freed of such material, may be discharged through the axially or centrally disposed fluid outlet which is of smaller diameter than the collector and may, if desired, be subjected to further separating action outside the chamber to remove a further quantity of solid material therefrom. The outer circumference of the centrifugal product collector is preferably spaced a considerable distance radially inwardly from the annular grinding zone into which the high velocity fluid jets are introduced, so that the above described centrifugal classifying action is maintained not only within the grinding zone, but also in an intermediate classifying zone, whereby particles which have not been sufficiently reduced in size are effectively prevented from inward entrainment to the product collector or to the central fluid outlet and are caused to recirculate in the grinding zone until sufficiently reduced. In some cases, the above described centrifugal product collector is omitted and all of the material which is sufficiently reduced is discharged with the entraining gaseous fluid through the centrally disposed outlet and may be separated and collected in any suitable manner outside the treatment chamber.

It is generally convenient and preferable to introduce the material to be pulverized into the treatment chamber at one or more positions inwardly of the zone of action of the high velocity jets, and preferably adjacent but within the inner boundary of the grinding zone, so that any material which is already sufficiently reduced to be entrained and carried inwardly by the spiralling fluid is not caused to be subjected to further grinding action, while particles of larger size are caused by centrifugal action to move outwardly into the grinding zone. Furthermore, it is generally convenient to introduce this material into the treatment chamber in suspension in a gaseous fluid having a component of motion in the direction of whirling fluid movement induced by the high velocity fluid jets.

Various arrangements of fluid jets in the grinding zone have been devised in various configurations of the peripheral walls of the grinding zone.

Generally the apparatus in the prior art required an excessively high rate of gaseous fluid supply to provide the necessary jet energy to be transferred to the particles for dissipation in the attrition action and friction of the whirling flow of the fluid.

The object of the present invention is to increase the effectiveness of attrition mill processes by creating a multiplicity of compact counter-turbulence impact currents of the gas-suspended material particles, requiring a minimum of gaseous fluid supply compared to that used by normal jet operation for a comparative rate of attrition energy delivered thereby.

A further object is to provide a high capacity compact apparatus for effectively pulverizing or reducing the particle size of a batch of material which may be wet, by attrition in a pulverizing chamber having means for producing a multiplicity of high speed counter-turbulence currents in closely adjacent areas throughout the chamber.

A further object is to include in the above compact apparatus, means for continuously separating and withdrawing of the smaller size particles from said chamber, and classifying flow-inducing means for these particles, so as to deliver only those particles which are sufficiently reduced in size, to a settling means, and returning the remaining particles to said pulverizing chamber, and continuously feeding new raw material to said chamber to

compensate for the amount of material delivered to the settling means.

A further object is to provide an annular paddle wheel rotating at right angles and close to high speed currents near the bottom of the pulverizing chamber for sweeping and discharging any heavy articles which have dropped out of the grinding chamber, back into the chamber for further pulverization, while providing a vortex of the lighter particles in the center of the paddle wheel for axial withdrawal therefrom into the inlet conduit of a classifying means in which the vortex action is continued to maintain only the finer particles in the central flow of the conduit which leads into the center of a centrifugal flow inducing means turning in the same direction as the vortex, the outer annular portion of the flow in the conduit leads into the central portion of a similarly driven centrifugal flow inducing means for connection to the return conduit to the pulverization chamber for recirculation therethru.

A further object is to provide an additional compact classifying means comprising a dual paddle wheel centrifugal fan for inducing flow therethrough mounted on the same drive shaft, one fan wheel portion having a central inlet from the central portion of the inlet conduit of the classifying means for receiving the central portion of the vortex flow in said conduit, the other fan portion having an annular inlet from the peripheral portion of the conduit for receiving the outer annular portion of the vortex flows in the conduit which contains the oversize particles for return to the pulverization chamber.

A further object is to arrange the mill, classifying means and settling means in a common base frame to provide portability to the apparatus as a unit, so that it may be transported by flat car or truck to places where it might be needed.

Other and more specific objects will become apparent in the following detailed description of the apparatus and its method of operation, as illustrated in the accompanying drawings, wherein:

FIG. 1 is a side elevational view of the attrition mill combination,

FIG. 2 is a plan view thereof,

FIG. 3 is a sectional view through the grinding chamber taken on the line 3—3 in FIG. 2, on an enlarged scale,

FIG. 4 is a sectional view therethrough taken on the line 4—4 in FIG. 3, on a further enlarged scale,

FIG. 5 is an enlarged sectional view of the paddle wheel in the bottom of the grinding chamber, taken on the line 5—5 in FIG. 1,

FIG. 6 is a detail sectional view of a portion of the paddle wheel taken on the line 6—6 in FIG. 5,

FIG. 7 is a detail sectional view of another portion of the paddle wheel taken on the line 7—7 in FIG. 5,

FIG. 8 is an enlarged sectional view through one of the fan wheels taken on the line 8—8 in FIG. 1,

FIG. 9 is a similar section through the other fan wheel taken on the line 9—9 in FIG. 1, and

FIG. 10 is a detail sectional view taken on the lines 10—10 in FIGS. 8 and 9.

In the illustrated embodiment of the invention a parallel-sided grinding chamber 20 is provided with a pocket 22 in its bottom for accommodating a paddle wheel 24 with a shaft 26 mounted in a bearing 28 on the forward side of the pocket and extending to a pulley 30 at its forward end for operation by a motor 32 through belts 34. A base frame 36 provides a support for the motor 32, pulverization chamber structure and other parts of the combination comprising the apparatus of the entire mill.

The material to be pulverized may be fed to the pulverization chamber by a screw conveyor 38 at a suitable rate, and bounces over the tops of a multiplicity of high speed rotating beater arms 40, their outer ends passing one another in closely adjacent radial planes. The beater

arms may be arranged in several radial planes axially spaced on one shaft 42 for passing other arms similarly arranged on one or more other shafts 44, the radial planes of which are axially offset with respect to those of the first beater arms, so that the other arms pass through the spaces between the radial planes of the first beater arms; so as to produce high speed counter-turbulence currents in the overlapping areas in the air causing a high rate of attrition pulverization of the material particles which break off from the pieces bouncing over the tops of the beater arm wheels in the upper portion of the pulverization chamber, and are carried down into these high turbulence areas by the milder turbulence in the intermediate areas of the chamber.

The ends of the beater rods 40 may have uneven or corrugated surfaces so as to increase the ricochetting effect on the particles and the air and to spread its turbulence, thus to provide a maximum rate of attrition per unit volume of chamber space. Only a minimum amount of material is ever sheared by simultaneous impact from its opposite directions, as in normal grinding operations and to some extent in vortex type attrition mills where some gas fluid jets are directed toward the peripheral wall of the grinding zone and produce a high incidence of crushing the particles circulating in contact with said wall by the bombardment of the high speed particles in the jet streams against these circulating particles producing a crushing impact thereon between the wall and the ricochetting particles from the jet streams. In applicant's novel method, the particles ricochet rapidly against one another and against the beater arms, receiving the high speed impacts only from one side at one time. Thus, while a considerably higher rate of attrition is achieved, frictional and shearing attrition is substantially eliminated. The attrition areas are substantially insulated from the walls of the chamber by more quiescent zones. The gentleness of this attrition method provides some valuable advantages over previous methods. It was found e.g. that the poison glands which are a part of the cotton seed could be separated without damaging the glands in the present attrition method.

The pocket 22 has a quiescent vortex zone in the central portion of the paddle wheel 24, from which the pulverized material in suspension in this vortex is withdrawn axially from the side of the pocket opposite that through which the shaft 26 extends, into the inlet conduit 46 of a classifying means 48. The classifying means includes a dual centrifugal fan wheel 50 for withdrawing the core portion of the vortex in the inlet conduit 46 with the finer particles in suspension and delivering this portion to the cyclones 52 through the delivery conduit 54, and for withdrawing the annular portion of the vortex flow containing the heavier particles in this portion and returning it to the pulverization chamber through return conduit 56, for further pulverization. The classification may be finely controlled by using a selected size of opening 58 in the inlet adaptor funnel 60 which is mounted on the inlet 62 to the delivery portion of the fan wheel 50. A damper valve 64 may be used at times when it is desired to cut off the delivery and recirculate all the material withdrawn from the pulverization chamber.

The delivery portion of the fan wheel 50 has fan blades 65 mounted on a backplate 66. The backplate is fixed to the drive shaft 68 which is mounted in bearings 70. These bearings, like bearings 28, may be spaced away from the casing in which the fan or paddle wheel operates, so as to insulate the bearings from the heat in the casings, which may reach a temperature of 1000° F. or more at times. The inlet 62 forms a cylindrical hub for the recirculating flow portion of the fan wheel 50 and is supported by radial braces 67 on shaft 68 to which it is fixed for common rotation by means of a pulley 72, belts 74 and motor 76. The recirculating flow portion of the fan wheel has fan blades 78 radially extending from the hub. The rotation of the fan wheel is in the same direction as

the vortex in the inlet conduit, whereby to assist in maintaining the vortex action to improve the separation to the desired degree in the inlet conduit, in accordance with the size of inlet opening 58 used in the adaptor funnel 60.

To maintain a steady output of the desired quality, an optimum load of the material is maintained in the pulverization chamber for most efficient pulverization, by feeding the material into the pulverization chamber at substantially the same rate that is delivered to the cyclones, after a proper selection of the size of the inlet opening 58 to the delivery fan portion and proper adjustment of speeds of operation of motors 32 and 76 have been made.

The gas fluid normally used in the present system is air and the pulverization chamber may be vented to the atmosphere so as to maintain substantially atmospheric pressure therein. By restricting the vent a subatmospheric pressure may be maintained to prevent explosions which could occur under some compression.

In some instances, as in the case of pulverizing substances like sulphur, it might be desirable to feed some inert gases into this vent to reduce the oxygen ratio in the gas fluid, or even to replace the air entirely by excluding the air and connecting the vent opening to a source of supply of the inert gas at a suitable slow rate. A closed system could be used by connecting a return conduit between the exhaust gas flow from the cyclones and the pulverization chamber, to conserve the gas fluid, if it is other than atmospheric air and is too expensive to waste by discharging into the atmosphere from the cyclones. Thus this system lends itself to efficient operation for pulverizing a variety of materials safely and without damage to those materials the minute particles of which are subject to being spoiled or harmed by harsh frictional scrubbing or crushing impacts.

The shafts 42 and 44 to which the beater arms are fixed, are mounted in bearings 80 outside the pulverization chamber and spaced from the opposite sides thereof to insulate them from the high temperatures of the chamber walls. A motor 82 may be mounted at one end of each shaft for operating the respective beater arm assembly at high speed in the same direction, preferably away from the recirculating inlet 84 at the top of the chamber.

The inlet conduit 46 is connected to the dual fan casing 90 by means of a telescopically fitting adaptor sleeve 86 with end flanges slidably fitting over the inlet conduit and the protruding inlet flanges 88 on the fan casing. Thus, the adaptor sleeve 86 may be slid back off the flanges 88, for cleaning and whenever the adaptor funnel 60 has to be changed. The adaptor funnels 60 have an inner end flange 92 which fits snugly within the outer end of inlet sleeve 63, which is rigidly fixed by struts 94 in the center of protruding inlet flange 88.

The cyclones 52 may be mounted on the same base frame 36 with the mill and classifying means to form a complete unit that may be readily transported to different sites, where it might be needed, close to the supply of the material to be pulverized.

The present system is ideally suited for the drying and treatment of material at very high temperatures, such as 1000° F. and more. It is also suitable for processing of explosive materials, such as sulphur, due to the fact that the material is under suction, not primarily under any pressure. Therefore, with the addition of a percentage of inert gas to the air used, safety of operation is achieved.

This system is also ideally suited for drying and pulverizing of raw organic material in its natural state, without any predrying, such as fresh agricultural products, fish, and chemicals which are of sensitive nature regarding high temperatures to which they cannot be normally subjected without burning. However, in the present mill, these materials can be processed at high temperatures, often over 600° F. without damage to their nutrient characteristics, due to the fact that the high velocity and

the moisture taken from the plant using a substantial amount of heat for its vaporization into steam, protect the material from burning. This same steam also carries with it the highly volatile properties which are ordinarily lost in milling and grinding. Therefore the steam when separated yields the volatiles if present, often in crystalline form in the dry powder product, deodorising the product to a degree.

This system is further ideally suited for drying and pulverization and chemical treatment of wet, sticky inorganic materials, such as clays of all descriptions, fullers earth, etc.

It is particularly suited for pulverization, drying and reduction to fine powder of ores of various minerals, providing the same ores are precrushed to a size not larger than about 4" so they may be readily fed by a screw conveyor, and in order that the same fine product can be prepared for flotation and leaching processes. By virtue of use of this type of mill, it is possible to coat particles with any chemicals which would help to speed up the processes of flotation and leaching.

The present system is further ideally suited for organic materials having a high oil content, such as cotton seed, peanuts, etc., inasmuch as we are able in this instance, by the passage of refrigerated air or other gases, to reduce these normally oily products to fine powder without clogging the machine. It was also found that in the present method, it is possible to separate the poison gland, which is a part of the cotton seed, from the seed itself without damaging the gland, as is often the case in other harsher milling processes.

This system is extremely well suited for delamination and pulverization of micaceous minerals, the same being processed in a steam medium.

It is ideally suited for the pulverization and activation of charcoal so that the porosity of charcoal is greatly increased by the removal of extraneous matter from the pores of the charcoal.

Also in the drying and pulverization of materials of an abrasive nature, due to the attrition of the particles by other abrasive particles, the abrasion on the machine parts is minimized particularly because the high speed counter-turbulence areas are separated from the chamber walls by more quiescent areas where the particles lose their energy before striking the walls of the chamber.

For many operations, there is no need for the recirculating a portion of the material withdrawn from the pulverization zone, if sufficient classification is obtained at the center of the paddle wheel vortex by controlling the size of the withdrawal opening. In those cases, the recirculating portion of the fan wheel and the return duct 56 could be omitted.

Many other obvious modifications in the details and arrangement of parts in this system may be made without departing from the spirit and scope of the present invention, as defined in the appended claims.

What is claimed is:

1. A continuous method of pulverizing material comprising enclosing a quantity of gaseous fluid with said material in a chamber,

60 creating a multiplicity of high speed counter-turbulence currents of particles of the material by batting and ricochetting them against other particles to reduce the particle size by attrition in closely adjacent zones throughout a central portion of the chamber space, thereby maintaining a relatively quiescent zone adjacent the walls of said chamber to insulate the walls against excessive wear by high speed impacts thereagainst by stray particles,

65 feeding gas and the material to be pulverized into the upper portion of said chamber at a suitable rate, withdrawing the pulverized material suspended in said gaseous fluid from the lower portion of said chamber at substantially the same rate as they are introduced thereto.

2. A method as defined in claim 1, in which the high speed counter-turbulence currents are created in a plurality of closely adjacent planes across the width of the chamber and in a plurality of closely spaced areas across the length and depth of the central portion of the chamber, said areas being separated from each other and from the periphery of the chamber by more quiescent zones.

3. A method as defined in claim 2, said pulverized material laden gaseous fluid being withdrawn from a suitably quiescent area in the lowest portion of said chamber.

4. A method as defined in claim 2, creating a vortex in the material laden gaseous fluid withdrawn from the bottom of said chamber to sweep the heavier particles from the periphery of said vortex back into suspension in said chamber for further pulverization therein and to create a quiescent center zone from which the pulverized material in suspension is further withdrawn and into which the quiescent area in the lowest portion of the chamber extends.

5. A method as defined in claim 4, and trapping any "tramp iron" or exceptionally heavy particles of the material in the bottom of said chamber.

6. A method as defined in claim 3, said pulverized material suspended in said gaseous fluid being withdrawn from the central part of the bottom portion of said chamber, rotating a large paddle wheel fan at high speed and at right angles to the planes of said high speed counter-turbulence currents, and

the rotation of the high speed paddle-wheel fan causing the heavier particles of material removed to travel in a peripheral path and be thrown back into the area of the high speed counter-turbulence currents for further attrition, and causing the lighter and smaller particles of material to rotate in the center zone from which area they are withdrawn under suction.

7. A method of reducing the size of particles of raw material to a fine powder without unduly injuring its molecular structure, comprising

subjecting the material to attrition by a succession of high speed batting and ricochetting impacts on particles of said material in turbulent suspension between moving parts passing each other at high speeds in parallel planes with small clearances between them and other batted and ricochetting particles in the center portion of a confined chamber having a funnel shaped bottom portion leading into a recess, said small clearances forming a virtual screen for substantially maintaining the larger particles in the upper portion of the chamber until they are broken up sufficiently,

creating a vortex peripherally sweeping the bottom of the recess and bringing the particles which have dropped out of the turbulent suspension back into the center portion for continued attrition, withdrawing the powder laden air from the center of said vortex in said recess,

separating the powder of the desired fineness from the coarser powder in this air and returning the remaining coarser powder back to the upper portion of the chamber.

8. A method as defined in claim 7, and feeding raw material to the upper portion of the chamber at a rate equivalent to the rate of withdrawal of the powder of the desired fineness to maintain an optimum loading in said chamber.

9. A method as defined in claim 8, and maintaining a suction in said chamber and throughout the entire apparatus by controlling supply of air thereto.

10. A method as defined in claim 9, operating said method in a closed system and using an inert gaseous fluid therein in place of air.

11. Apparatus for particle size reduction of pulverulent materials comprising

a pulverizing chamber having a reduction zone with said materials in turbulent suspension in the central portion of the chamber and a funnel shaped lower portion with a recess in the bottom thereof,

5 a rotating means having its lower peripheral portion extending into said recess for sweeping drop-out portions of said materials from said recess in the bottom of said chamber back into suspension in said central portion, said rotating means creating a vortex centrally thereof,

10 an outlet from the lower portion of said chamber at the center of said vortex, classifying means having centrifugal flow-inducing means with an inlet conduit connected to said chamber outlet and an outlet conduit for delivering the flow of fine particles to a separating and collecting means.

12. Apparatus as defined in claim 11, including a separating and collecting cyclone device connected to said 20 outlet conduit from said classifying means, and a common platform frame for supporting all of said apparatus, whereby it may be handled as a portable unit for transportation on flat beds to sites where it is needed.

13. Apparatus as defined in claim 11, said classifying 25 means including a dual flow centrifugal fan, with concentric inlet conduits, the outer inlet conduit being connected by a vortex transfer conduit to the said chamber outlet, the portion of the fan with the outer inlet conduit having a second outlet conduit which is connected to said 30 pulverizing chamber for recirculating the coarser particles received from the outer annular part of the vortex conduit back into the chamber for further pulverization.

14. Apparatus as defined in claim 13, and a valve in 35 said inner inlet conduit diverting the entire flow into the recirculating conduit when the valve is fully closed, for further batch mixing in the pulverizing chamber to obtain homogeneous distribution of minute proportions of important ingredients in the batch.

15. Apparatus as defined in claim 13, said inner inlet 40 conduit being adapted to receive an exchangeable nozzle selected from a group having different size inlet openings, whereby the proportion of the flow recirculated for further pulverization may be controlled as desired for any run of material.

16. Apparatus as defined in claim 11, said pulverizing 45 chamber having high-speed counter-turbulence producing beater means for continuous bombardment of particles against each other and ricochetting against said beater means producing said turbulence in the reduction zone in areas spaced from the walls of said chamber by more 50 quiescent areas.

17. Apparatus as defined in claim 15, said beater means comprising a plurality of beater arm wheels rotating in the same direction on spaced axes and having peripheral 55 portions of their radially extending beater arms moving in opposite directions in closely adjacent planes.

18. Apparatus as defined in claim 17, said beater arm 60 wheels having substantially parallel shafts mounted in the pulverizing chamber in spaced relation so as to provide an overlap of the peripheries of adjacent wheels, each wheel having a series of beater arms operating in a plurality of axially spaced radial planes, and the beater arms of one wheel having their planes of operation axially staggered with relation to those of the adjacent wheel so 65 as to move in closely adjacent planes in opposite directions, when the wheels are rotated in the same direction.

19. Apparatus for pulverizing raw material by attrition 70 comprising a chamber, a plurality of rotating beater assemblies, each assembly having a plurality of beater arms operating in closely adjacent planes with beater arms of other assemblies rotating on spaced axes and moving past each other in opposite directions at high speeds in a central portion of said chamber to create 75 counter-turbulence currents of particles batted and rico-

cheted between said arms and against each other, means for feeding said material into the upper portion of said chamber and means for withdrawing pulverized material in suspension from a more quiescent zone in the lower portion of said chamber away from said concerted currents.

20. Apparatus as defined in claim 19, in which the beater assemblies rotate on axes spaced so as to provide a substantial radial overlap of the ends of the passing arms.

21. Apparatus as defined in claim 20, wherein said spaced axes are parallel.
